UNITED STATES PATENT OFFICE.

JULES WEINBRENNER, OF THANN, FRANCE.

RECTILINEAR COMBING MACHINE.

Application filed June 6, 1925, Serial No. 35,461, and in France October 3, 1924.

The present invention relates to rectilinear combing machines and it has for its general object to provide novel means for increasing the output of the machine. The invention is 5 applicable wholly or in part to any kind of rectilinear combing machine but more especially to Nasmith and like combining machines.

In the ordinary rectilinear combing machine the output is limited by the thickness of the sliver which the nipper is capable of holding and according to the present invention I am able to increase the output of the machine by providing means supplementary to the nipper to assist the latter in holding the sliver during the combing of the head and during the drawing-off operation. In the construction shown this supplementary sliver-holding means is in the form of a supplementary comb which is situated between the upper jaw of the nipper and the feed roller and co-operates with the lower jaw of the nipper.

Another feature of the invention relates to 25 the feed roller. The feed roller as ordinarily constructed is merely a fluted roller which functions only as a feed member. According to the present invention this roller is especially constructed so that it not only functions as a feed roller but also assists in holding the sliver during the combing of the head and to prevent portions of the sliver from passing below the fixed comb during the drawing-off.

35 The accompanying drawing shows by way of example constructional forms of supplementary retaining means in accordance with the invention applied to a Nasmith or like combing machine.

40 Fig. 1 shows in section the nipper with a supplementary comb mounted on the upper jaw and a shoulder formed on the lower jaw, the feed roller and the usual top comb and detaching rollers being also shown in section and a portion of the periphery of the circular comb being indicated by a dot-and-dash line.

Fig. 2 shows a slightly different construction of the lower jaw of the nipper.

50 Fig. 3 shows supplementary means for co-operating with the feed roller.

Fig. 4 shows a new form of feed roller for a Nasmith combing machine.

55 Figs. 5 and 6 show in section and in elevation a variation of the construction of the upper jaw of the nipper shown in Fig. 1, and

Fig. 7 shows another constructional form of the invention.

In Fig. 1, *a* is the circular comb, *b* the upper jaw and *c* the lower or inner jaw of the nipper, *t* the detaching rollers, and *u* the top comb and *f* the feed roller. These parts, with the exception of the feed roller and the lower jaw *c* of the nipper, may have the construction usually found in rectilinear combing machines.

One feature of my invention relates to means situated between the feed roller and the upper jaw of the nipper to engage the sliver and augment the action of the nipper 70 in holding the sliver during the action of the circular comb. The device herein shown for this purpose is a supplementary comb and in Fig. 1 this supplementary comb is indicated at *d* and is secured to the upper jaw 75 *b* of the nipper, the supplementary comb *d* being constructed so that when the jaws are closed said comb will engage the lap or sliver. To ensure that this supplementary comb *d* enters well into the lap or sliver, the 80 lower jaw *c* is formed at a suitable point with a projecting part or shoulder *e*, and the comb *d* is mounted so that it makes an angle a little greater than 90° with the said jaw on the feed side. When this comb *d* is pressed 85 well into the lap it prevents the lap from slipping when acted on by the circular comb.

Instead of providing the projection *e*, a groove *g* may be formed in the lower jaw *c* (Fig. 2) into which the head of the supplementary comb *d* projects a little, this arrangement ensuring also that the comb enters sufficiently far into the lap.

As already mentioned, the feed roller used on Nasmith and like machines can only 95 serve to feed the lap, being simply fluted, whereas in accordance with the present invention the said roller is so formed that, without affecting its efficiency as the feed member, it assists in retaining the lap during the combing of the head and then during the drawing-off. For these purposes the acting surface of the roller is formed with peripheral and transverse grooves, as shown in Fig. 4, so that the said surface is as it were 100 studded with small pyramids. These pyramidal projections may be formed by embossing or milling or in any other way.

The grip of the feed roller during the combing of the head and then during the 110 drawing-off is still further increased by providing means which co-operates with the

feed roller *f* to cause the lap to embrace the roller on a considerable portion of its circumference. One way of accomplishing this is shown in Fig. 3 and consists of a straight-edge *h* situated behind the feed roller *f* and over which the lap passes. The presence of this straight-edge will cause the lap to engage the feed roller on at least a quarter of its circumference and the feed roller thus augments the action of the nipper and the supplementary comb in holding the sliver during the operation of the circular comb. The straight-edge *h* is preferably adjustable in relation to the feed roller *f*. Other means than the straight-edge may be employed for causing the sliver to engage a considerable portion of the circumference of the feed roller without in any way departing from the invention.

26 Figs. 5 and 6 show a construction of the upper jaw *b* of the nipper which may be adopted. Instead of providing the supplementary comb *d*, the heel *i* of the said jaw is formed or provided with teeth or projections to form a comb. The result obtained is similar to that obtained by means of the comb *d*.

The constructional form of the invention shown in Fig. 7 comprises a supplementary comb which is independent of the upper jaw *b* of the nipper. This supplementary comb *k* is shown as provided with two rows of teeth *l*, but it may have only one row, or several rows; it is carried by a two-armed lever which is mounted on a spindle *n* journaled in brackets *o*. A spring *q* bears against one arm *m*¹ so that it presses the comb *k* towards the lower jaw *c* of the nipper. The other arm *m*² carries at its free end a roller *r* which, influenced by an inclined plane *p*, gives to the comb *k* a movement analogous to the movement of the upper jaw. This arrangement may be varied, or it may be replaced by some other mechanism that ensures the putting into action of the supplementary comb at the required times.

I claim:

1. In a rectilinear combing machine, the combination with a circular comb, a nipper, a feed roller, of means situated between the nipper and the feed roller to engage the sliver and assist the nipper in holding said sliver during the combing of the head and during the drawing-off.
- 55 2. In a rectilinear combing machine, the combination with a circular comb, a nipper, and a feed roller, of a supplementary comb situated between the nipper and the feed roller and adapted to engage the sliver and assist the nipper in holding the latter during

the combing of the head and during the drawing-off.

3. In a rectilinear combing machine, the combination with a circular comb, of a nipper comprising upper and lower jaws, a feed roller, and a supplementary comb situated between the upper jaw of the nipper and the feed roller and co-operating with the lower jaw to engage the sliver and assist the nipper in holding the latter during the combing of the head and during the drawing-off.

4. In a rectilinear combing machine, the combination with a circular comb, of a nipper comprising upper and lower jaws, a feed roller and a supplementary comb carried by the upper jaw and co-operating with the lower jaw to assist the nipper in holding the sliver during the combing of the head and during the drawing-off.

5. In a rectilinear combing machine, the combination with a circular comb, of a nipper comprising upper and lower jaws, a feed roller, and a supplementary comb situated on the feed side of the upper jaw and co-operating with the lower jaw to assist the nipper in holding the sliver during the combing of the head and during the drawing-off.

6. In a rectilinear combing machine, the combination with a circular comb, of a nipper comprising upper and lower jaws, a feed roller, and a supplementary comb situated on the feed side of the upper jaw and forming therewith an angle a little greater than 90°, said lower jaw having a re-entrant portion with which the teeth of the supplementary comb co-operate, whereby said supplementary comb assists the nipper in holding the head during the combing of the head and during the drawing-off.

7. In a rectilinear combing machine, the combination with a circular comb, of a nipper, a feed roller having its surface formed with radially-arranged pyramidal projections, and means co-operating with the feed roller over which the sliver is fed to cause the sliver to embrace said roller on an appreciable arc of its periphery.

8. In a rectilinear combing machine, the combination with a circular comb, of a nipper, a feed roller having its surface formed with radially-arranged pyramidal projections, and a straight-edge adjustably mounted directly behind the feed roller and between which and the feed roller the sliver passes, whereby the sliver has contact with a considerable portion of the periphery of the feed roller.

In testimony whereof I signed hereunto my name.

J. WEINBRENNER.
